CLAIM

The ornamental design for a rice mold, as shown and described.

DESCRIPTION

FIG. 1 is a perspective view of a rice mold; FIG. 2 is a front view of the rice mold of FIG. 1, a back view being a mirror image thereof;

FIG. 3 is a right side view of the rice mold of FIG. 1, a left side view being a mirror image thereof;

FIG. 4 is a top view of the rice mold of FIG. 1;

FIG. 5 is a bottom view of the rice mold of FIG. 1;

FIG. 6 is a cross-sectional view thereof, taken along line 6-6 in FIG. 2;

FIG. 7 is a cross-sectional view thereof, taken along line 7-7 in FIG. 3;

FIG. 8 is an exploded perspective view of the rice mold of FIG. 1, showing an inner mold frame and an outer base plate; and,

FIG. 9 is a bottom view of the inner mold frame of FIG. 8.

1 Claim, 9 Drawing Sheets
